INKSTAND

Gustav J. Sengbusch, Milwaukee, Wis.

Application May 18, 1940, Serial No. 335,910

9 Claims. (Cl. 120—59)

This invention relates to improvements in inkstands and more particularly to inkstands of the type wherein a relatively large supply of ink is stored in a receptacle and a relatively small quantity of ink contained in a dipping well which automatically receives a supply of ink from the receptacle in such a way that the depth of the ink in the well is maintained substantially constant.

The main objects of the invention are to provide an inkstand of the character indicated wherein the main ink receptacle may be a more or less standard, commercially available, small bottle of ink such as is usually purchased for use in homes and other places where a small supply of ink is ordinarily sufficient; to provide an inkstand wherein such a bottle of ink may readily be combined with a permanent part in such a way as to constitute, in effect, a complete desk set which has all the appearances of a wholly factory-made set; to provide an inkstand of the character indicated which will effectively retain in the main receptacle the bulk of the ink supply in such a way that if the inkstand should accidentally be upset, only a minimum amount of ink will be free to be spilled out; to provide an inkstand of the character indicated in which means are provided for supporting a pen in conveniently accessible upright position with its pen point partially immersed in ink so as to be instantly ready for withdrawal for writing purposes; to provide an arrangement whereby the pen point, although immersed to only a very shallow depth in ink, will nevertheless receive a substantial supply of ink so as to be capable of extended writing without requiring repeated dipping; and to provide an inkstand of the type indicated which may be manufactured economically and at very low cost.

Other objects and advantages of the invention will be understood by reference to the following specification and accompanying drawing wherein there is illustrated a selected embodiment of the improved inkstand.

In the drawing:

Fig. 1 is a plan, the main ink receptacle or ink bottle being removed and omitted;

Figs. 2 and 3 are sections on the lines 2—2 and 3—3, respectively, of Fig. 1 but showing the main ink receptacle or ink bottle in operative position;

Fig. 4 is a section on the line 4—4 of Fig. 3;

Fig. 5 is a perspective of an element of the structure; and

Fig. 6 is a fragmentary plan.

Referring now to the drawing, the improved inkstand comprises a main base part 10 which may conveniently be made of molded rubber or other composition material which has the capacity of withstanding corrosion by ink. With the base part 10, there is associated an ink bottle 11 which may be of glass, the same being employed in inverted position after being supplied with a special form of stopper 12. The base 10 is further provided with a pen socket 13 for receiving and positioning a pen 14 in conveniently accessible position.

The main ink receptacle or bottle 11 is, in this instance, a round bottle and it may be one of the commercially available bottles of about two-ounce size which when furnished is provided with a screw cap secured to the bottle by means of external screw threading 15 provided on the neck 16 of the bottle.

20 The special stopper 12 is preferably made of a good grade of rubber which will not be affected by ink and, as shown in the drawing, is in the form of a fairly thick disc having a main body portion 17 adapted to be inserted in the neck of the bottle, the outside size of said body portion being such as to fit fairly snugly in the bottle.

25 The stopper also includes an outer end portion 18 which extends beyond the periphery of the inner portion 17 so as to constitute a peripheral flange for engagement with the mouth end of the bottle to limit insertion of the stopper thereinto. The stopper is provided in its inner portion with a centrally disposed recess 19, the same being 30 preferably of circular form and the outer portion of the stopper is provided with a narrow elongated opening 20 which extends substantially diametrically of the stopper. In one practical device, the opening 20 measures from $\frac{5}{16}$ " to $\frac{3}{8}$ " in 35 length and about $\frac{3}{64}$ " in width.

40 The opening 19 is provided instead of continuing the narrow elongated aperture 20 completely through the stopper so as to facilitate the passage of ink through the opening 20. The opening 20 is of such size that it constitutes a capillary control for the flow of ink from the bottle. With the stopper in place in the bottle, the bottle containing ink may easily be inverted without spilling a single drop, particularly if the bottle 45 is turned about an axis which extends parallel with the length of the opening 20. In that manner but little chance is provided for air to flow into the bottle through one side of the opening while ink is flowing across the same.

55 The main base 10 of the structure is so formed

as to provide a chamber 21 which receives the bottle, the bottom 22 of the chamber being inclined downwardly and inwardly toward a centrally disposed, upstanding boss 23. The boss 23 is made of a predetermined height and it is adapted to constitute a seat for the inverted ink bottle which rests thereon through the agency of its stopper as clearly shown in the drawing.

The upstanding boss 23 is provided with a diametrically extending slot 24, the same being, in one practical embodiment of this construction, about $\frac{1}{8}$ " in width and being tapered in depth as best shown in Figure 3 so as to provide a slanted or downwardly and forwardly inclined bottom 25. As shown in Figure 3, the slot 24 in the forward portion of the boss extends through the full thickness or depth of the boss so that the bottom 26 of said forward portion of the slot is on the same level as the bottom 27 of a well 28. The well 28 extends forwardly and communicates at its front end with the lower end of the pen socket 13 as clearly shown in Figure 3.

For locking the bottle 11 in place in the base 10, a suitable screw 29 may be threaded through a wall portion of the base in such a manner that its inner end will engage the neck of the bottle immediately above an external rib 30. The base 10 is further provided with a supporting formation 31 of any suitable configuration which provides a relatively wide dimension which is so related to the height of the inkstand including its bottle as to provide adequate, non-tipping support for the device. Said supporting structure 31 also embraces the pen socket 13 as clearly shown.

The pen socket 13 in this instance is of generally tapering form, the forward wall portion 32 thereof being substantially straight (vertically) and of inverted conical form. The upper rear portion of the pen socket 13 is also of inverted conical form, constituting a continuation of the upper front part of the socket but the lower rear or outer portion of the socket is preferably flattened transversely as indicated at 33 and humped inwardly so as to be adapted to cooperate with the flattened under-side 34 of a feed bar 35 which is carried by the pen 14. Suitable ribs such as indicated at 36 are provided for engaging the lower end portion of the pen as illustrated, thereby to maintain said portion of the pen in centrally disposed position in the socket with air passageways such as indicated at 37 intermediate the ribs all around the pen.

The venting of the socket in this manner has the beneficial effect of eliminating or reducing accumulation of ink on the end of the pen holder, whereby the latter is maintained relatively clean. The socket arrangement is such that when the pen holder is in its rest position in the socket the lower end or nib 38 of the pen point will be immersed in ink contained in said well 28, the front face 39 of the pen point engaging the lower front wall portion 40 of the socket. Such engagement between the pen point and the wall of the socket cooperates with the seating of the pen holder in the upper end of the socket to hold the pen holder in predetermined, upstanding, conveniently accessible position.

The flattened hump portion 33 of the socket serves to cooperate with the back of the feed bar 35 to insure positioning of the pen with the front of the pen point in engagement with said wall portion. In the normal removal of the pen from the socket and replacement thereof in the

socket, it is found that the pen is ordinarily grasped substantially in the way in which the pen is held for writing purposes, and then returned to the socket without having been turned in the fingers to any substantial extent. Hence, when the pen is replaced it is ordinarily inserted in the socket in such a position that the flattened back of the feed bar will be in cooperative relation to the flattened humped portion of the socket to insure the said positioning of the pen in the socket.

It will be observed that even though the pen is rotated to a certain extent, the interengaging portions of the feed bar and socket portion will tend to cam the pen to its position of rotary alignment with the front of the socket. Only in the event that the pen is rotated to an unusual degree will the back of the feed bar and flattened humped portion of the socket fail to operate in the manner indicated. In that event the pen very noticeably fails to resume its proper seated position and the person using the pen may readily correct the pen position.

In one commercial embodiment of the described structure it is found that the pen may be turned approximately 90 degrees in either direction from its normal seated position without preventing proper operation of the described arrangement for effecting rotary alignment of the pen.

A device constructed as above described operates to supply ink from the bottle to the well 28 and it is found that the ink does not ordinarily rise above the greatest depth of the well 28, i. e., the depth thereof adjacent the outer wall of the chamber 21, substantially as indicated by the broken line 41 in Figure 3. The nib of the pen point is thus immersed and it is found that capillary action causes the ink to rise upwardly on the pen point, such capillary action being increased when the ink reaches the wall portion 40 of the socket. The capillary action produced by cooperation of the wall portion 40 of the socket and the adjacent surface of the pen point serves to carry ink upwardly by capillary action to an extent which insures a sufficient supply of ink to permit extended writing therewith without repeated dipping. Some of such ink finds its way through the usual slit and opening in the pen point into the slots of the feed bar 35. The feed bar structure may be substantially the same as that shown in my Patent No. 1,915,338.

Ink is delivered from the receptacle 11 through the slot 20 in the stopper and through the slot 24 in the supporting boss 23 incident to a capillary action along the walls of said slots 20 and 24. It appears that ink tends to creep down the walls of the stopper slot 20 and finds its way into the slot 24, creeping down the walls thereof. The inclined bottom 25 of a portion of the slot 24 serves to cause ink to accumulate in the small wedge-shaped space indicated at 42 between the bottom 25 of the slot 24 and the adjacent surface of the stopper, such accumulation of ink serving as a sort of lead for inducing continued flow of ink under normal circumstances. The opening 20 in the bottle stopper is closed against the entrance of air into the bottle 11 by ink which tends to pile up within the slot 24 of the boss 23, so that ink does not normally reach a depth in the bottom chamber 21 which would bring the level of ink up to the bottom of the stopper.

Under normal conditions the level of ink does not rise above the level indicated by the line 41.

Under varying temperature and pressure conditions of the atmosphere, the level of ink may change somewhat and even when ink is displaced from the bottle incident to high temperature or low pressure, the amount of ink so displaced is received in the entire area of the chamber below the bottle stopper, so that such displaced ink is spread out over a wide area with the result that the depth of ink in the well 28 does not vary to an objectionable extent.

For insuring proper alignment of the bottle stopper opening 20 with the slot 24, the bottle stopper is preferably provided with one or more recesses 43 (in this instance a pair of such recesses) which are respectively adapted to receive upstanding pins 44 formed integrally with the boss 23. The pins 44 may be of such size that they fit frictionally in the openings 43 and thereby tend to hold the bottle steadily in position in the base structure 10, but it is preferable that they be not such a tight fit that the stopper will be held in the base when the bottle is removed therefrom.

The opening through which the pen socket 13 communicates with the chamber 21 of the base may be of any form, it being shown in this instance as of inverted V-shape (see Figure 4), the same being incidental to the intersection of the conical socket opening 13 with the chamber 21. The opening may be specially shaped otherwise if desired.

The base of the described structure may be made very inexpensively by a well-known molding process in which suitable material is delivered under pressure to a form which will produce the entire base structure as an integrally constructed chamber completely finished upon removal from the mold. If desired, suitable rubber feet may be attached to the base which may be provided with suitable feet-receiving sockets molded integrally therewith as indicated at 45, the same being located at suitable places in the base structure. The rubber stopper member may also be molded and cured to produce a completely finished member in a single operation and, of course, the bottle 11 is an obviously inexpensive part of the structure.

The base may be initially furnished with a bottle and stopper which is made to fit the base and which bottle may be filled from any other supply of ink, or the base may be sold in connection with a full bottle of ink of the proper size to fit the base. A full bottle of ink may be furnished with the described rubber stopper in place covered by a screw cap secured to the neck of the bottle in the manner already explained, so that when the purchaser is ready to set up the inkstand, all that is required is to remove the screw cap, and invert and insert the bottle in the base.

The base may, of course, be made for use in connection with other shapes of bottles and it is not essential that the bottle actually fit the shape of the chamber 21 so long as it will accommodate a stopper which may be properly seated on the raised boss 23. The interengaging pins and sockets 44, 43, may be relied upon either wholly or in part to hold the bottle in its proper upright position and any interengagement of the walls of the bottle with the upstanding walls of the base may be sufficient for maintaining a bottle in operative position in the base.

Changes in the described structure may obviously be made without departing from the principles embodied therein, and the following claims

are intended to be construed with reference to the said principles rather than to the specific details of the structure.

I claim:

5. 1. In an inkstand of the class described, a receptacle having a pen socket communicating therewith, an ink bottle in said receptacle provided with an ink outlet in its lower end, said ink outlet being of relatively small size so as to resist the free flow of ink therethrough, means formed on the bottom of said receptacle for association with said outlet opening and adapted to assist the flow of ink through said opening by capillary action, and cooperating means carried by the lower end of said bottle and the bottom of said receptacle for positioning said bottle with its outlet opening in operatively aligned relation to said means.
10. 2. In an inkstand of the class described, a receptacle having a pen socket communicating therewith, an ink bottle in said receptacle provided with an elongated ink outlet in its lower end, said ink outlet being of relatively small size so as to resist the free flow of ink therethrough, means formed on the bottom of said receptacle for association with said outlet opening and adapted to assist the flow of ink through said opening by capillary action, and cooperating means carried by the lower end of said bottle and the bottom of said receptacle for positioning said bottle with its outlet opening in operatively aligned relation to said means.
15. 3. In an inkstand of the class described, a receptacle having a bottom wall provided with an ink well and with an elongated slot for conducting ink to said well, there being also a pen socket associated with said receptacle and communicating with said well, an ink bottle having a wide mouth and provided with a removable stopper, said stopper having an elongated ink outlet slot, said ink bottle and stopper being insertable in inverted position in said receptacle with said outlet slot substantially in register with said slot in the bottom of the receptacle, and means for insuring such registration of said slots comprising an interengaging pin and hole in said stopper and receptacle bottom.
20. 4. In an inkstand of the class described, a receptacle having a bottom wall provided with an ink well and with a passageway for conducting ink to said well, there being also a pen socket associated with said receptacle and communicating with said well, an ink bottle seated in inverted position in said receptacle so as to deliver ink to said passageway, a screw threaded through the wall of said receptacle and adapted to engage said bottle, the latter having an external rib underlying said screw, whereby the bottle is locked to said receptacle, and interengaging means carried by the outlet end of said ink bottle and the bottom of said receptacle for resisting lateral displacement of the bottle by said screw.
25. 5. In an inkstand of the class described, a receptacle and a pen socket communicating at its lower end with said receptacle, said socket being disposed at an angle to the vertical whereby a pen disposed in said socket will tend to fall in such direction as to cause the pen point to engage the forward portion of the socket, thereby to provide between said pen point and socket portion capillary ink feeding means adapted to carry ink upwardly on said pen point, and means in the lower portion of said socket for insuring rotary positioning of the pen with the top or

front of the pen point adjacent said socket wall portion.

6. In an inkstand of the class described, a receptacle and a pen socket communicating at its lower end with said receptacle, a pen having a pen point and a flattened-back feed bar associated with said pen point, said socket being disposed at an angle to the vertical whereby a pen disposed in said socket will tend to fall in such direction as to cause the pen point to engage the forward portion of the socket, thereby to provide between said pen point and socket portion capillary ink feeding means adapted to carry ink upwardly on said pen point, and means comprising a transversely flattened wall portion formed in the lower portion of said socket for cooperating with the feed bar of the pen to effect disposition of the pen in the socket with the front of the pen point adjacent said socket wall portion.

7. In an inkstand of the class described, a receptacle and an ink bottle having an outlet opening in its lower end, means in the bottom of said receptacle normally registering with said outlet opening for cooperating therewith to discharge ink from the bottle, a screw threaded through a wall portion of said receptacle and adapted to engage said bottle for locking the latter in place in said receptacle, said bottle and receptacle being provided with interengaging means for resisting lateral displacement of the bottle by said screw so as to maintain said first mentioned means and outlet opening in said registered relationship.

8. In an inkstand of the class described, a re- 35

ceptacle having a bottom wall provided with an ink well and an elongated slot for conducting ink to said well, an ink bottle having a mouth and being provided with a stopper having an elongated ink outlet slot, said ink bottle and stopper being insertable in inverted position in said receptacle with said outlet slot substantially in register with said slot in the bottom of the receptacle, a screw threaded through the wall of said receptacle for engaging said bottle to lock the same in the receptacle, and interengaging means carried by the outlet end of said ink bottle and the bottom of said receptacle for resisting lateral displacement of the bottle by said screw and maintaining said registration of said slots.

9. In an inkstand of the class described, a receptacle and a pen socket communicating at its lower end with said receptacle, said socket being disposed at an angle to the vertical whereby a pen disposed in said socket will tend to fall in such direction as to cause the pen point to engage the forward portion of the socket, thereby to provide between said pen point and socket portion capillary ink feeding means adapted to carry ink upwardly on said pen point, and loosely interfitting means carried by said pen and socket, respectively, for automatically, as an incident to insertion of the pen, effecting sufficient rotary adjustment of the pen to insure its positioning in the socket with the top or front of the pen point adjacent said forward portion of the socket.

GUSTAV J. SENGBUSCH.
